UNITED STATES PATENT OFFICE.

JOHN M. McCRAY, OF PUEBLO, COLORADO.

BUTTON-KNIFE.

1,380,226.

Specification of Letters Patent. Patented May 31, 1921.

Application filed October 19, 1920. Serial No. 417,958.

To all whom it may concern:

Be it known that I, JOHN M. McCRAY, a citizen of the United States, residing at Pueblo, in the county of Pueblo and State 5 of Colorado, have invented certain new and useful Improvements in Button-Knives, of which the following is a specification.

My invention relates to means for removing buttons from shoes, garments and other 10 articles, and comprises a cutter to sever the button and a holder to receive and retain the severed buttons, the object being to provide a cutter easily and conveniently manipulated, easily kept in order, and into 15 which the buttons, when severed, are conveniently directed without danger of loss.

Referring to the accompanying drawing, which illustrates my invention:

Figure 1 is a perspective view of my im- 20 proved cutter.

Fig. 2 is a side view cut away at the base to show the interior chamber which receives and holds the severed buttons.

Fig. 3 is a transverse section on the line 25 3-3 of Fig. 1, and

Fig. 4 is a longitudinal section on the line 4-4 of Fig. 3, showing the device in its relation to a button being severed.

1 designates a cylindrical tube open at one 30 end, which I will denominate the front end, to form a receptacle or holder for buttons. This tube is to be held in the hand of the user and it has one side cut away at its front end as at 2, to enable the thumb of the user 35 to be pressed down into the concavity of the projecting end. Near one edge of the projecting end is formed an elongated slot 3, extending in a longitudinal direction, and having an opening 4 at one side.

40 On the outside of the projecting end of

tube 1, and at the uncut side of the slot 3, is a cutting blade or plate 5 secured in place by removable clamping screws 6-6, its cutting edge projecting slightly inward beyond the edge of the slot so that it may sever the 45 thread which holds the button before the edge of the slot can reach the same. When the cutter 5 becomes dull, it may, by removing the screws 6-6, be taken off and sharpened. The device is used in the following 50 manner:

The user grasps the tube 1 in his hand, placing his thumb over, or into, the concavity of the projecting front end; then he applies it to the button to be removed in 55 such way as to pass the projecting end under the button and pass the thread holding the button through the opening 4, and then presses his thumb down upon the button to hold the same and keep it from flying away 60 when severed, and to pass it back into the receptacle. In case the thread is not easily cut by pressing the cutter against it the device may be moved back and forth (the slot 3 permitting such movement), the cutter 5 65 then acting in the manner of a saw.

Having thus described my invention, I claim:

A device for removing buttons from shoes or fabrics, the same comprising a tubular 70 cylindrical member having one side cut away to form a semi-tubular projection, said projection being provided with an elongated longitudinally extending slot having an opening at one side, and a cutter blade at 75 the opposite side of the slot.

In testimony whereof, I affix my signature hereto.

JOHN M. McCRAY.
